PEDAL COVER

Arthur B. Jones, Detroit, Mich.

Application October 9, 1940, Serial No. 360,355

5 Claims. (Cl. 74—563)

This invention relates generally to steam presser apparatus for pressing fabrics and more particularly to foot pedal pads therefor.

In clothes or fabric steam presses, and particularly large commercial types of presses, a foot pedal is provided by means of which the operator moves the presser head down and locks it against the steam table to steam and press material therebetween. Because of the size of these machines, it requires considerable force to operate the pedal, and, further, the operator receives a jar each time the presser head is locked in place. As a result, operation of such presses is very tiring and operators complain of aching leg muscles. Furthermore, operation of the pedal for any length of time is very hard on the operator's shoes, which is, of course, objectionable. In addition, it quite often occurs that the operator's foot slips off the pedal before the presser head is locked down against the steam table, with the result that the pedal flies up and in many cases injures the operator's leg.

Accordingly, it is an object of the present invention to provide for pedals of steam presses, a foot pad which will overcome the above mentioned objections.

A further object of the invention is to provide an attachable foot pad for a steam presser operating pedal and one which is inexpensive to manufacture and easily replaceable.

Other objects of the invention will become apparent from the following detailed description taken in connection with the accompanying drawing, in which:

Figure 1 is a side view showing generally a steam presser having a foot operated pedal with my foot pad thereon;

Figure 2 is an enlarged side view of my foot pad and a portion of the pedal arm;

Figure 3 is a top plan view of the foot pad;

Figure 4 is a cross-sectional view of the foot pad and pedal arm, taken along the line 4—4 of Figure 2;

Figure 5 is a side view similar to Figure 2 of a modified form of foot pad; and

Figure 6 is a cross-sectional view of the pad and pedal arm, taken along the line 6—6 of Figure 5.

Referring to the drawing by characters of reference and first to Figure 1, there is shown a steam presser which includes a base or standard 10 from which upright standards 11 extend, only one of which standards is shown. Below the upper ends of the standards 11 a horizontal sup-

port 12, integral therewith, supports a steam table, designated in general by the numeral 13, which steam table may be of any suitable type insofar as the present invention is concerned. 5 Pivoted to the upper ends of the standards on a shaft 14, a pair of levers 15, of which only one is shown, carry at corresponding or like ends thereof a presser head 16 which in operation of the presser is brought down against the upper surface of the steam table 13. The lever 15 is provided with a rearwardly extending arm 17 to which one end of a connecting or push rod 18 is connected, the other end of the rod 18 being connected to one end of a pedal lever or treadle 19 which is pivoted intermediate its ends to the uprights 10 on a shaft 20. From the shaft 20, the lever 19 has a forwardly extending arm 21, on one end of which is usually provided a metallic foot pedal 22 on which the operator steps to swing lever 15 to lower the presser head 16 against the upper surface of the steam table 13. A spring 22a having one end secured to the lever arm 17 and the other end anchored to an integral lug 23 of the standard 11 is provided for returning the lever 15 to its raised position or the position shown in Figure 1.

In order to lessen the jar received by the operator upon lowering of the pressure head 16 and also to decrease wear of the operator's shoes, I provide a resilient foot pad, designated in general by the numeral 24, which foot pad may be readily fitted over the metallic pedal 22 and be rigidly secured to the lever arm 21. Referring first to the foot pad structure of Figs. 2 to 4 inclusive, this structure includes a metallic holder 25 which is preferably formed of sheet metal having a bottom wall 26 provided with an upturned flange 27 extending preferably continuously around the entire outer periphery of the bottom wall 26. A resilient foot pad 28, preferably made of rubber, is fitted into the holder 25 and is of a thickness greater than the depth of the holder flange 27 such that the pad extends above the flange or such that the operator's foot will engage only the rubber pad. The pad 28 is made in the same form, defined by the inner surface of the holder flange 27, but is made slightly larger around its periphery than the distance around the inner periphery of the flange 27. In assembling the holder 25 and the foot pad 28, the pad is forced or pressed into the holder 25 and is held thereto solely by the compression forces in the pad 28, thereby eliminating the necessity for cement or other attaching means to hold the pad in place. As shown, the

pad holder 25 is of elongated form, and welded or otherwise secured to the underside of the holder there is preferably a pair of longitudinally spaced, metallic straps 29 and 30 extending transversely of the holder 25. Adjacent the sides of the holder 25 the straps 29 are provided with depending end portions or flanges 31 to straddle the pedal and the pedal arm 21, the straps and the flanges 31 preferably being formed of a spring sheet metal. Adjacent their lower ends the oppositely disposed flanges 31 are provided with aligning apertures to receive a bolt 32 on one end of which a nut 33 is screwed down to draw the flanges 31 toward each other for detachably securing the foot pad holder 25 to the pedal or to the pedal arm. Usually the pedal and pedal arm are provided on the underside thereof with a longitudinally extending reinforcing rib 34, and, in order to insure against the foot pad slipping along the pedal arm, I locate the bolt apertures in the flanges 31 such that the bolts 32 will engage the underside of the rib 34, causing the bolts to be placed under a strain and to be bent slightly intermediate their ends, as illustrated in Figure 4. By placing the bolts 32 under tension, as above pointed out and illustrated in Figure 4, it will be seen that the frictional force between the bolt and the rib 34 of the pedal arm will aid in preventing slipping of the foot pedal unit from the desired position.

Referring now to the modified form of the foot pad shown in Figures 5 and 6, this pad differs from the previously described foot pad in that the forward flanges, as at 35, of the holder instead of being drawn toward each other by a bolt are bent inwardly toward and around against the undersurface of the pedal arm, as illustrated in Figure 6. This construction is less expensive than the first described foot pad and is more easily attached to the foot pedal since it is only necessary to tighten one nut after the foot pad has been slipped onto the end of the pedal.

In operating a steam presser I have found that the herein described resilient foot pad materially decreases the shock formerly received on operating the foot pedal, with the result that the work of an operator is less tiring, that the chances of the operator's foot slipping off is practically eliminated, and that wear of the operator's shoes is materially decreased. In addition to the above advantages, I have provided a resilient foot pedal which is so constructed that its cost will not be prohibitive to the average presser operator, and, further, have provided a foot pedal which is easily and securely attached to the pedal and one which may be readily replaceable, if necessary. For purposes of illustration the present invention has been shown and described in connection with a steam presser, but it will be understood that the foot pad may be employed on the treadle of any kind of machine, for example, on the treadle of a welding machine.

While I have shown and described my invention in detail, it is to be understood that the same is to be limited only by the appended claims for many changes may be made without departing from the spirit and scope of the invention.

What I claim is:

1. In a machine having a pedal lever and a pedal for moving a head member down against a support, a removable attenuated foot pad unit coextensive with the pedal and lever comprising a holder for seating on the pedal projecting therebeyond in a direction of the pedal lever, means for clamping the holder to the pedal, and a resilient pad pressed into said holder and held therein solely by the compression force.

2. In a steam presser having a pedal lever and a pedal for moving a presser head against a steam table, a foot pad unit for the pedal comprising a holder having an upturned flange around the outer periphery thereof, said holder being coextensive with the pedal and pedal lever, a rubber pad forced into said holder and held thereto by the expansion force of the compressed rubber acting against the inner surface of the flange, a strap for holding the holder to the pedal lever and clamping means for attaching the holder to the pedal.

3. In a steam presser having a pedal and a pedal lever with a convex under-surface for moving a presser head against a steam table, a removable foot pad unit for the pedal comprising, an elongated holder for seating on the pedal, a resilient pad in said holder, a pair of downturned resilient flanges secured to and depending from said holder adjacent opposite sides thereof for straddling the pedal lever, and means for extending beneath the pedal lever and drawing the flanges toward each other to secure the holder to the pedal lever, said means being deformed by the convexity of the under-surface of said pedal lever to clamp said holder to said pedal.

4. In a steam presser having a pedal and a pedal lever with a convex under-surface for moving a presser head against a steam table, a removable foot pad unit for the pedal comprising, an elongated holder coextensive with the lever and pedal, spaced straps secured to the underside of said holder for seating on the pedal, said straps extending transversely of the holders and having downturned resilient end portions at opposite sides of said holder, and means for urging the end portions of each strap toward each other beneath said holder to secure said holder to the pedal lever and to the pedal, said means being deformed by the convexity of the under-surface of said pedal lever to clamp said holder to said pedal.

5. In a steam presser having a pedal lever and a foot pedal for moving a presser head down against a steam table, a foot pad for the pedal comprising, a recessed elongated holder coextensive with the pedal lever and pedal, a rubber foot pad held in said holder, a forward strap secured to the underside of the holder, said strap extending transversely of said holder and having downturned end portions for clamping the holder to the pedal, a rear strap secured to the underside of said holder and having downturned resilient end portions for straddling the pedal lever, and means including a bolt for extending beneath and engaging the underside of the pedal and pedal lever and drawing said end portions toward each other to secure the holder to the pedal.

ARTHUR B. JONES.
